UNITED STATES PATENT OFFICE

ERIC OLIE SCHJOLIN, OF BIRMINGHAM, MICHIGAN, ASSIGNOR TO GENERAL MOTORS CORPORATION, OF DETROIT, MICHIGAN, A CORPORATION OF DELAWARE

RADIATOR SUPPORT

Application filed September 8, 1927. Serial No. 218,281.

The invention relates to motor vehicles, and more particularly to a novel and improved mounting for the radiator comprising a part of the cooling system of an internal combustion engine.

The customary practice heretofore followed in the construction of motor vehicles, has been to mount the radiator structure directly on the front end of the chassis frame, the inlet and outlet thereof communicating by means of rubber tubing or hose connections with the water jacket of an internal combustion engine located behind the radiator, and which is also carried by the chassis frame. Since the radiator and engine are individually mounted at the different places longitudinally of the frame, the occurrence of twisting or weaving of the chassis frame, incident to travel over rough roadways, causes these units to move or tilt to different extents, throwing the respective inlet and outlet openings out of line, and thereby straining the rubber hose connections. Such frame weaving also tends to distort and strain the radiator core assembly, eventually resulting in breakage which necessitates costly repairs and replacements. Side sway of the radiator due to frame weaving is especially pronounced in the case of large trucks and buses and not uncommonly extends throughout a range of several inches.

One of the primary objects of the present invention is to provide a mounting which will enable the radiator structure to be entirely relieved or freed of frame weaving and the harmful effects thereof, and which materially reduces the extent of side sway.

A further object is to provide a flexible support for the radiator to cushion road shocks and other vibrations, as for instance, those set up by the inherent unbalanced forces of an internal combustion engine.

A further object of the invention is to provide for the adjustment of the position of the radiator in proper relation with the engine, and to thereafter tie or brace the radiator in such definite position, whereby the hose connections will not be subjected to strains and distortion.

50 The above and other objects and advan-

tages of the invention, as will be apparent in the following specification, are obtained in the present instance, by flexibly mounting the lower part of the radiator directly on the engine rather than on the frame as has been 55 the custom, and to employ divergently extending adjustable brace rods at the upper part of the radiator, as will now be described in detail.

In the accompanying drawing, Figure 1 60 is a front elevation of a radiator mounted in accordance herewith, the flexible mounting at the bottom thereof being shown in section, and the braces at the upper end in dotted outline; Figure 2 is a side elevation of the construction shown in Figure 1, and Figure 3 is 65 a top plan view of a modified bracing arrangement.

Referring to the drawing the reference character 1, indicates an internal combustion 70 engine of the type employed for propelling motor vehicles, supported by and between a pair of longitudinal chassis frame members 2-2, and the numeral 3 refers to the cooling 75 radiator therefor, taken as a whole. Projecting forwardly beneath the central part of the radiator from the engine and bolted thereto as at 4, is an L-shaped bracket or supporting member 5, which for convenience and economy of manufacture, may be 80 stamped or otherwise formed of sheet metal. A flexible or spring plate 6 is secured at an intermediate point by bolts or rivets 7, to the horizontal portion of the bracket 5, and extends transversely beyond either side 85 thereof, on the outer ends of which the radiator rests, being secured thereto by hold-down bolts 8. These bolts 8 extend upwardly through openings in the spring plate, and pass through the flange or ledge 9 of the radiator shell or casing 11, and into threaded engagement with the underside or bottom wall of the lower tank 12 of the radiator. Suitable washers or spacers 13 carried by the 90 bolts, are interposed between these parts, and coil springs 14 surrounding the bolts between the heads thereof and the bottom of the spring plate, serve to yieldingly maintain or hold the radiator on the spring plate 6. 95 Drainage of the liquid within the cooling 100

system is effected by removal of the plug 15, threaded into the lower tank 12 from the front of the vehicle, where it is readily accessible. The lower tank 12 is also provided with an opening or passageway 16, extending therethrough for the insertion of the engine starting crank, indicated by dotted lines in Figure 2.

The rear portion of the upper or top tank 17 of the radiator, is provided with reinforcing or supporting brackets or ears 18, secured on the under side thereof from whence they extend downwardly and outwardly toward the shell 11, being secured thereto as by rivets 19. Tie rods, preferably in the nature of adjustable turnbuckles 20, are connected at one end as at 21, to these ears or brackets 18, and at their other end to the head of the engine as indicated at 22. These tie rods diverging from the engine to the outer parts of the radiator serve to firmly brace the radiator with respect to the engine. Obviously, the relative adjustment of the connections permits a wide range of movement of the top 25 of the radiator with respect to the engine, both to and fro and sidewise, to accommodate various conditions of use, and to enable proper alignment of the water passageways and hose connections, as well as the adjustment 30 of the radiator with respect to the dashboard and cowl to correctly fit the engine hood or bonnet.

In lieu of turnbuckles connecting the upper end of the radiator with the engine, use 35 may be made of the modified arrangement illustrated in Figure 3, wherein rearwardly divergent tie rods brace the top of the radiator from the dashboard. These tie rods 23—23, preferably of angle iron, are connected at their forward ends with the plate 40 or extension 24 at the upper central portion of the radiator, and at their outer ends are provided with a threaded stud 25, which projects through the dashboard 26 and carries 45 fastening nuts threaded thereon, to permit adjustment of the brace rods to properly locate the radiator.

From the above description, it will be apparent that the single central point of support 50 for the spring plate at the bottom of the radiator, insures maximum and full resilient action of the mounting, and since the radiator structure is entirely independent of the frame, its relation to the engine remains 55 the same regardless of frame weaving. At the same time, the obliquely extending tie rods effectually brace the radiator in all directions, and by their relative adjustment 60 permit the positioning of the radiator to be properly effected.

While the invention has been described more or less specifically, it is to be understood that it is not limited to the exact 65 details shown, but that various modifications

may be made as come within the scope of the appended claims.

I claim:

1. In a motor vehicle, the combination with an engine and a radiator, of a flexible member interposed between the radiator and engine and secured to one thereof at its ends and to the other thereof at an intermediate point to flexibly support the radiator adjacent the bottom thereof on said engine, and a rigid brace connection between the top of the radiator and the engine. 70

2. In a motor vehicle, the combination with an engine and a radiator, of a supporting member projecting forwardly from the engine beneath the central part of the radiator, an element secured to and extending transversely of said member beyond either side thereof and loosely connected with the radiator, and a tie rod connection between the engine and radiator. 80

3. In a motor vehicle, the combination with an engine and a radiator, of a forwardly projecting bracket carried by the engine, a spring plate connected at a central point on said bracket and projecting there-beyond, yielding fastening means holding the radiator on the ends of said plate, and an adjustable connection between the radiator and engine for permitting adjustment of the radiator toward and from said engine. 90

4. In a motor vehicle, the combination with an engine and a radiator, of a bracket rigidly connected to said engine and projecting forwardly beneath said radiator, a transverse spring plate connected at an intermediate point to the bracket and at its ends to the radiator, and means to fixedly brace the upper part of the radiator in definite relation with said engine. 100

5. In a motor vehicle, the combination with a chassis frame, an engine supported on the frame and a radiator, of a bracket rigidly connected to said engine and projecting forwardly beneath said radiator, means extending transversely of the bracket beyond the sides thereof to flexibly connect the radiator on said bracket, and a pair of tie rods extending divergently from the engine to the upper part of the radiator. 110

6. In a motor vehicle, the combination with an engine and a radiator, means for yieldably supporting the lower portion of the radiator at the center thereof on said engine, and a pair of divergently extending tie rods connecting the upper portion of the radiator adjacent the sides thereof with said engine. 115

7. In a motor vehicle, the combination with a chassis frame, an engine supported on the frame and a radiator, of a forwardly projecting member carried by the engine, a spring plate connected at an intermediate point to said member and at its outer ends to the lower part of the radiator, and a pair of obliquely extending brace rods connecting the 120 125 130

upper portion of the radiator with said engine.

8. The combination set forth in claim 7, wherein said brace rods are provided with means to permit relative longitudinal adjustment thereof.

9. In a motor vehicle, the combination with an engine and a radiator, of a supporting bracket projecting forwardly from the engine beneath the central bottom portion of the radiator, a transverse member resting on said bracket and extending beyond both sides thereof, yieldable connections between said member and the radiator at points spaced from the bracket, and bracing means for the top portion of said radiator.

10. The combination set forth in claim 9, wherein said transverse member comprises a resilient plate.

11. The combination set forth in claim 9, wherein said bracing means comprises adjustable members for varying the position of the radiator.

12. In a motor vehicle, the combination with an engine and a radiator, of a supporting bracket projecting forwardly from the engine beneath the central bottom portion of the radiator, a spring member carried by the bracket and projecting transversely beyond either side thereof, fastening bolts passing loosely thru openings in the ends of said spring member and into threaded engagement with the bottom of said radiator, and coil springs surrounding said bolts and yieldingly maintaining the radiator on said member.

13. In a motor vehicle, the combination with an engine and a radiator, of a supporting bracket projecting forwardly from the engine beneath the central bottom portion of the radiator, a spring member carried by the bracket and projecting transversely beyond either side thereof, fastening bolts passing loosely thru openings in the ends of said spring member and into threaded engagement with the bottom of said radiator, coil springs surrounding said bolts and yieldingly maintaining the radiator on said spring member, and a pair of adjustable tie rods extending divergently from the engine to outer and upper portions of said radiator.

14. Means to free a radiator structure from the damaging stresses incident to frame weaving, road shocks and the like, including in combination with a radiator and an engine, of a bracket projecting forwardly from the engine, a spring plate secured at a central point and extending transversely beyond the sides of the bracket, and means to loosely fasten the radiator on the ends of said plate.

15. Means to free a radiator structure from damaging stresses incident to frame weaving, road shocks and the like, including in combination with a chassis frame, an engine supported therein, and a radiator of a forwardly

projecting bracket on the engine, a member secured to and extending transversely of the bracket beyond either side thereof, and a yieldable connection between the radiator and said member.

70 In testimony whereof I affix my signature.

ERIC OLIE SCHJOLIN.
